Primary Examiner — L. A. Grabenstetter*Assistant Examiner* — Bethany Louise Mallino(74) *Attorney, Agent, or Firm* — Kunzler Bean & Adamson, PC; Michael Bartholomew**CLAIM**

The ornamental design for a cabinet as shown and described.

DESCRIPTION

FIG. 1 is a front, right and top perspective view of a cabinet in a closed position, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the cabinet in an open position of use.

FIG. 10 is an enlarged view of detail 10 in FIG. 1.

FIG. 11 is an enlarged view of detail 11 in FIG. 1; and, FIG. 12 is an enlarged view of detail 12 in FIG. 1.

The dashed broken lines depict portions of the cabinet that form no part of the claimed design. The dot-dash broken lines in FIGS. 1 and 10-12 depict the boundaries of the enlargements and form no part of the claimed design.
